CONTROL VALVE

Woodrow A. Hasbany, South Bend, Ind., assignor to
Clark Equipment Company, a corporation of
Michigan

Filed Feb. 6, 1961, Ser. No. 87,214
7 Claims. (Cl. 137—596.12)

The present invention relates to valves and more particularly to directional control valves for either single or double acting hydraulic cylinders.

Conventional directional control valves for hydraulic cylinders, either of the single or double acting units, frequently permit the load on the hydraulic unit to drop or otherwise yield unavoidably of its own weight as the valve is operated. In single acting cylinders this is the result of communication through the valve between the source of pressure and the pressure side of the cylinder before sufficient pressure in the valve has been reached to equal or exceed the counter force applied by the load on the unit. Various types of check or poppet valves have been employed in directional control valves between the control element and the cylinder, to prevent back flow in the system while this inadequate pressure condition exists and until the pressure of the fluid from the supply pump or other source has increased sufficiently to meet the demands of the load on the hydraulic unit. These check valves, however, have the disadvantage of often opening suddenly when the required pressure has been reached, causing jerky operation and ineffective control of the hydraulic cylinder unit. This condition likewise prevails in double acting hydraulic cylinder units; however, these latter units have the further disadvantage when controlled by the conventional directional valve of cavitating on the high pressure side of the piston as a result of a rapid and excessive withdrawal of hydraulic fluid from the low pressure side of the piston. Check and poppet valves have also been employed in the conventional valves to control the return of fluid from the low pressure side; however, controlling the operations of the latter valves to obtain proper timing and smooth operation of the hydraulic cylinder has been difficult and frequently ineffective. It is therefore one of the principal objects of the present invention to provide an effective, relatively simple and compact directional control valve of the spool type for either single or double acting hydraulic cylinders, in which leakage of fluid from the hydraulic cylinder, and consequently load drift, are positively prevented, and in which no load drop occurs in the hydraulic cylinder when the valve is actuated to operate the cylinder.

Another object of the invention is to provide a directional spool valve for double acting cylinders having a poppet and check valve mechanically actuated, hydraulically operated mechanism in the hydraulic fluid lines to each end of the cylinder, which facilitates accurate and effective control of the hydraulic cylinder by the operator, and which prevents cavitation and avoids load drop at the beginning of and during the operation of the hydraulic cylinder.

Still another object is to provide a directional control spool valve having a pilot operated poppet valve which positively prevents leakage from the hydraulic cylinder unit while the unit is in the hold position, and in which continued use creates "wear in" and results in more effective operation, thus permitting wider manufacturing tolerances, both in the poppet and spool valve elements, reducing service requirements, and increasing substantially the life of the valve over conventional spool valves.

A further object of the invention is to provide relatively easily fabricated directional control valves for either

2

single or double acting hydraulic cylinders and in either series or parallel circuits, which are free of hunting and chattering, and which permit accurate, effective and reliable control of the cylinders, regardless of normal variations in available operating fluid pressures.

Another object of the present invention is to provide a comparatively simple and relatively inexpensive directional control valve having poppet valves in the lines to the cylinders, which will consistently open in response to moderate pump pressures regardless of load created back pressures.

Another object is to provide a novel poppet valve for use in directional control valves, which can be easily assembled and serviced and which can be effectively used in conjunction with a number of different types of basic control valves.

Additional objects and advantages of the present control valve will become apparent from the following description and accompanying drawings, wherein:

20 FIGURE 1 is a cross sectional view of a directional control valve of dual spool, in series arrangement and open center type, embodying my invention;

25 FIGURE 2 is a cross sectional view of the valve shown in FIGURE 1, taken on line 2—2 of the latter figure, illustrating one form of my poppet valve and showing the spool valve in its neutral hold position;

30 FIGURE 3 is an enlarged cross sectional view of one of the poppet valves shown in FIGURE 2, taken on line 3—3 of said figure, showing the valve in a different operating position;

35 FIGURE 4 is a cross sectional view of a modified form of poppet valve embodying my invention, the section being taken on a line corresponding to the sectional view of FIGURE 2;

40 FIGURE 5 is a cross sectional view of another modified form of poppet valve embodying my invention; and

FIGURE 6 is a cross sectional view of a further modified form of valve, illustrating the present invention.

Referring more specifically to the drawings, numeral 40 designates the body of an open center valve having two spool valves 12 and 14 therein in series arrangement for controlling two separate double-acting hydraulic cylinders, one of which is diagrammatically illustrated at numeral 16. The two spool valves 12 and 14 contain spools or plungers 13 and 15, respectively, and are supplied with hydraulic fluid from a pump or other suitable source (not shown) through a port 18, the fluid flowing from port 18 through passage 20 to spool valve 12 and then through passage 22 to spool valve 14. The open center of valve 45 12 is connected with a tank return passage 24 and port 26 by passages 22 and 28, passages 20, 22 and 28 being in direct communication with one another when the two spool valves are in their neutral hold position, as shown in FIGURES 1 and 2. Spool valve 12 is connected with one end of cylinder 16 by passages 30 and 30' and with the other end of the cylinder by passages 32 and 32', and spool valve 14 is connected with one end of another double acting cylinder (not shown) similar to cylinder 16 by passage 34 and with the other end of the respective cylinder by passage 36. Passage 20 is also connected to

50 passage 24 for returning fluid to the tank through a pressure relief valve 40, the construction and operation of which will be described in greater detail hereinafter. The valve illustrated in the drawing is suitable for a variety 55 of different types of hydraulic systems, the one shown being designed to control two double acting hydraulic cylinders of well known construction, and forming a part of a system having a tank and a positive displacement pump for supplying hydraulic fluid from the tank to the valve and thence through the lines to both ends of the double acting hydraulic cylinders. The pump is continuously operating and the fluid from the pump is returned

60

directly to the tank while the valve spools are in their neutral hold position as shown in FIGURES 1 and 2. The hydraulic system and the components thereof, aside from the valve, form no part of the present invention and will not be described herein.

In the spool valve 12, the bore has a series of lands separating the aforementioned passages for pump and tank fluid, including lands 50 and 52 between pump pressure passage 20' and open center fluid return passage 22 and passage 20" and passage 22, respectively, lands 54 and 56 between passage 20' and passage 30 leading to one end of the hydraulic cylinder and between passage 20" and pressure passage 32 leading to the other side of the hydraulic cylinder, and lands 58 and 60 between passage 30 and return passage 24 and between passage 32 and passage 24, respectively. On spool 13 are lands 62, 64 and 66 for controlling the flow of fluid through the open center connecting passages 20 and 22 and from passage 20 to passages 30 and 32, and lands 68 and 70 for controlling the fluid return from passage 30 to passage 24 and from passage 32 to passage 24, respectively. The spool is manually operated by a lever (not shown) connected to spool extension 72 and is returned to neutral hold position from either fluid delivery position by a centralizing means 74 consisting of a coil spring 76 disposed around an extension 78 of the spool, and reacting at one end against a retainer 80 seated against a shoulder 82 on the spool and shoulder 83 in the valve body, and at the other end against a spring retainer 84 mounted on the end of extension 78 and seating against cap 86 threadedly received in the valve body. As spool 13 is shifted, for example to the left as viewed in FIGURES 1 and 2, retainer 80 which is seated against shoulder 82 is moved with the spool, and since retainer 84 is held by cap 86, spring 76 is compressed, and on release of the spool by the operator, will return the spool to its neutral hold position. When the spool is shifted to the right, spring retainer 84 is picked up by a collar 90 on extension 78 and is moved with the spool, and since retainer 80 is seated against shoulder 83, spring 76 is thereby compressed. On release of the spool by the operator, the spring returns the spool to its neutral hold position.

In the spool valve 14, the bore has a series of lands separating the aforementioned passages for pump and tank fluid, including lands 90 and 92 between pump pressure passage 22' and open center fluid return passage 28 and passage 22" and passage 28, respectively, lands 94 and 96 between passage 22' and passage 34 leading to one end of a hydraulic cylinder and between passage 22" and pressure passage 36 leading to the other end of the hydraulic cylinder, and lands 98 and 100 between passage 34 and return passage 24 and between passage 36 and passage 24, respectively. On spool 15 are lands 102, 104 and 106 for controlling the flow of fluid through the open center connecting passages 22 and 28 and from passage 22 to passages 34 and 36, and lands 108 and 110 for controlling the fluid return from passage 34 to passage 24 and from passage 36 to passage 24, respectively. The spool is manually operated by a lever connected to spool extension 112, and is held in any selected operating position by a detent mechanism 114 consisting of a hollow cap 116 secured to body 10 in axial alignment with the bore of the spool valve and having a series of annular grooves 118, 120, 122 and 124 in the internal surface for retaining the spool in its neutral hold position, in position to move the piston of the hydraulic cylinder in one direction or the other, and in position for free floating of the hydraulic cylinder, respectively. Cooperating with the foregoing grooves for retaining the spool in the desired position are plunger pins 126 and 128 seated in a transverse bore 130 of the spool assembly and urged radially outwardly by a coil spring 132 reacting at opposite ends against the two pins. As shown in FIGURE 1, bore 130 is disposed in a cylindrical member 134 secured to the end of the spool in axial alignment therewith by

a stem 136 joined to the member and threaded into a recess 138 in the end of the spool. Various other types of detents than the one shown may be used in conjunction with spool valve 14.

Passages 30 and 32 for delivering fluid to the two ends of hydraulic cylinder 16 contain poppet valves 150 and 152, respectively, of identical construction and operation, these two valves functioning to prevent leakage of fluid from the ends of the hydraulic cylinder, and consequently to prevent load drift while the valve is in the neutral position, and to avoid load drop by the hydraulic cylinder and cavitation in the cylinder while the cylinder is being operated. Since the two poppet valves are the same, only one will be described in detail, using the same numerals of one with primes to identify the parts of the other. The two valves are seated in cylindrical chambers 154 and 154' interposed, respectively, along the side of the spool between passages 30 and 30' leading to one end of hydraulic cylinder 16 and between passages 32 and 32' leading to the other end of the cylinder, the chambers having ports 156 and 156' defined by annular valve seats 158 and 158' and threaded connections 160 and 160', respectively, for hydraulic fluid lines to the two ends of the cylinder.

Poppet valve 150 consists of a hollow cylindrical element 162 having a frusto-concally shaped surface 163 for engaging valve seat 158 and reciprocably supported in chamber 154 by a cup-shaped retainer 164, which in turn is supported by its outwardly extending flange 166 seated on shoulder 168 of the valve body. The flange, which is perforated or slotted at numerals 170 to permit the fluid to pass freely through chamber 154, is held rigidly against shoulder 168 by the hydraulic line coupling (not shown) threaded into connection 160. The hollow interior of element 162 is connected with passage 30 by an orifice 172 in the closed end of the element and with chamber 154 and consequently with passage 30' and one end of cylinder 16 by one or more small calibrated orifices 174 in the side of retainer 164 beyond the edge of element 162 when the element is in its seated position as shown in FIGURE 2. The flow of fluid through orifice 172 is controlled by a conically-shaped valve member 176 urged to its seat in the orifice by a coil spring 178 reacting against the internal side of the valve member and a cup-shaped retainer 180 in the hollow interior of element 162. The spring also urges element 162 to its seat. A stem 182 is attached to valve member 176 and extends through orifice 172 and passage 30 into contact with a shoulder 184 on the spool. Retainer 180 contains a number of longitudinal grooves 186 in the external side walls to permit the hollow interior of element 162 to communicate freely with orifices 174 when the element is not in its retracted position. When the spool is in its neutral hold position, as shown in FIGURE 2, stem 182 is perpendicular to the axis of the spool and radially outward from its reduced diameter portion 188, and the valve member is in position to fully close orifice 172. As the spool is moved from neutral hold position to the left, shoulder 184 engages the free end of stem 182 and moves or swings it to the left, cocking and/or retracting valve member 176 sufficiently to open orifice 172 and permit high pressure fluid to flow from the interior of element 162 through passages 30 and 24 and thence through port 26 to the tank. This reduction in pressure within element 162 permits the now higher pressure acting on conical surface 163 to fully retract the element from its seat to the position shown in FIGURE 3.

In order to prevent chattering and hunting of valve element 162 while fluid is flowing through port 156 to the cylinder, orifices 174 are so placed with respect to the adjacent edge of element 162 that when the element is fully retracted from its seat the orifices are closed by the element, thus preventing momentarily the return of fluid into the hollow interior and consequently preventing the

return of the element to its seat by spring 178. When the spool is returned to its neutral hold position blocking passage 30, fluid under back pressure from the cylinder in passage 30' and chamber 154 flows through a small orifice 190 in the end of retainer 164 into the hollow interior of element 162 and with the assistance of spring 178 urges element 162 to its seat 153. In order to prevent fluid from bleeding through orifice 190 while the element is lifted from its seat, i.e. while fluid is being admitted into the respective end of the cylinder, a valve means 192, consisting of a ball seated in a recess in the adjacent end of retainer 180 and urged into the inner end of the orifice by spring 178, closes the orifice except when removed from its seat by the aforementioned back pressure immediately following return of the spool to neutral hold position.

In the operation of the foregoing spool valve structure 12 containing the poppet valves, movement of the valve to the left as viewed in FIGURES 1 and 2 blocks the open center passage 22 and connects passage 20 with passage 32 and simultaneously connects passage 30 with passage 24. As the spool moves to the left, shoulder 184 engages the free end of stem 182, thereby opening valve 176 and permitting fluid to drain through orifice 172 from the interior of valve element 162. This reduces the pressure in the interior of the element sufficiently to permit the pressure on conical surface 163 within chamber 154 to unseat element 162 and permit fluid to flow from the respective end of cylinder 16. Simultaneously, fluid from the pump passes from passage 20 into passage 32 and reacts against the end of poppet valve element 162', first temporarily opening valve 176' and then lifting the element from its seat and retracting it until orifices 174' are fully covered by the edge of element 162'. With the element in this position, the pressure on the external surface of element 162' is sufficiently greater than the combined internal fluid pressure and pressure of spring 178' that the element remains in its fully retracted position as illustrated in FIGURE 3 as long as passages 20 and 32 are in communication. As soon as the spool is returned to its neutral hold position by centralizing means 74, valve 176 closes, permitting the pressure in the interior of element 162 to become substantially equal to the pressure on its external surface, and hence permitting spring 178 to seat the element and close port 156. Simultaneously, the back pressure in passage 32' and chamber 154' opens valve means 192' and fluid passes through orifice 190', thereby increasing the pressure in the interior of element 162' sufficiently to permit spring 178' to seat the element and close port 156'.

Pressure relief valve 40 determines the maximum pump pressure available for operation of the hydraulic cylinders and consists of a sleeve 193 seated in a bore 194 in body 10 and held therein by a threaded cap 195. The sleeve contains a reciprocable hollow element 196 urged to its seat 198 by a coil spring 200 reacting between the internal side of the element and a fixed partition member 202 within the sleeve. When the element is fully seated, it closes opening 204 in the end of the sleeve, and when the element is open, i.e. retracted to the right as viewed in FIGURE 1, opening 204 and a port 206 along the side of the sleeve connect passage 20 with fluid return passage 24. The interior of element 196 is connected with passage 20 by a restricted orifice 208 in the end of the element and with passage 24 by a tubular member 210 and passages 212 and 214, the tubular member being rigidly supported by partition member 202 and having a restricted orifice 216 in the end thereof. The tubular member contains a ball valve 218 which controls the flow of fluid through orifice 216, and which is urged to its seat about the orifice by a coil spring 220 reacting at one end against the ball valve and at the other end against an adjustment means 222 for varying the pressure required to open the valve. When the pres-

sure in passage 20 is less than the maximum pressure desired, element 196 remains seated about opening 204 and ball valve 218 remains seated about orifice 216, and the pressure in the interior of the element is equal to the pressure in passage 20. If the pump pressure in passage 20 and the interior increases sufficiently to unseat ball valve 218, the pressure in the interior of the element immediately decreases, permitting the higher pressure in passage 20 reacting on the external end of the element to retract the element from its seat and establish communication through opening 204 and port 206 between passage 20 and fluid return passage 24, thus immediately reducing the pressure in passage 20. Fluid passing slowly through restricted orifice 208 again re-establishes an equilibrium in pressure between passage 20 and the interior of element 196 and spring 200 seats the element and fully closes opening 204.

In some instances in which the hydraulic cylinder is heavily loaded, shifting of the spool to its rightward position, thus opening poppet valve 152 and permitting fluid to drain from the respective end of the cylinder, permits the piston to advance at a greater rate than the delivery of fluid from the pump to the opposite end of the cylinder. In the conventional control valve this condition produces cavitation in the end of the cylinder to which lines 30 and 30' are connected. In the present unit passage 30' is connected with the tank through chamber 154, passages 230, 232 and 24, and port 26. A valve consisting of an element 234 urged to its seat 236 by a spring 238 at one end of passage 232 permits the flow of fluid from the tank, under the foregoing condition, and provides sufficient fluid to the cylinder to prevent cavitation. Valve element 234 prevents the back flow of fluid from the cylinder through passages 230 and 232.

In FIGURE 4 a modified and simplified version of the present invention is illustrated, consisting of a chamber 240 interposed between passages 30 and 30' and having an annular valve seat 242 and a hollow cylindrical valve element 244 with a conical surface 246 for engaging seat 242. Element 244 is supported by a cup-shaped retainer 248 rigidly secured in the end of chamber 240. The hollow interior of element 244 is connected by an orifice 250 with passage 30 and by a restricted orifice 252, with passage 30', the former orifice being controlled by a valve member 254 urged to its seat in the orifice by a coil spring 256 and opened by a stem 258 as the spool is moved to the left as viewed in FIGURE 4. An external coil spring 260 around the element is preferably provided to prevent or minimize hunting and chattering of element 244. When the valve member 254 is opened, the pressure in the interior of the element is reduced to sufficiently permit the pressure in chamber 240 acting on the external surface of the element to retract the element from its seat. When the spool is returned to its neutral hold position, the fluid flowing through orifice 252 equalizes the internal and external pressures on the element and thereby permits spring 256 to seat the element.

The modified form shown in FIGURE 5 is substantially the same as that shown in the preceding figure with the exception of the pilot valve; hence, like numerals are used to identify like parts. In this form a more positive seal is obtained between the pilot valve 262 and a valve seat 264 by the use of an O-ring 265 seated in an annular groove 266 in a disc-shaped part 268 of the valve. In the operation of this pilot valve, part 268 and the O-ring are lifted perpendicularly from their seat by a stem 270 sliding on an inclined surface 272 on the spool. The operation of this poppet valve is otherwise the same as the one shown in FIGURE 4.

FIGURE 6 discloses a further modified form of the present invention, consisting of a chamber 280 interposed between passages 30 and 30' and having an annular valve seat 282 and a hollow cylindrical valve element 284 with a conical surface 286 for engaging seat 282.

Element 284 slides on and is supported by a cylindrical retainer 288 mounted rigidly in the end of chamber 280. The hollow interior of element 284 is connected by a tubular protrusion 290 and an orifice 292 with passage 30 and by a restricted orifice 294 and the hollow interior of retainer 288 with passage 36', orifice 292 being controlled by a ball valve 296 urged to its seat in the orifice by a coil spring 298 mounted on a guide pin 300 extending from retainer 288. The ball when fully seated at the bottom of protrusion 290 projects through orifice 292 and engages a tapered surface 302 on the spool for unseating the ball. An external coil spring 304 around the element is preferably provided to prevent or minimize hunting and chattering of element 284. When ball valve 296 is opened by tapered surface 302 as the spool is shifted to the left, the pressure in the interior of the element is reduced sufficiently to permit the pressure in chamber 280 acting on the external surface of the element to retract the element from its seat. When the spool is returned to its neutral hold position and the fluid flowing through orifice 294 equalizes the internal and external pressures on the element, spring 298 seats the element and closes the passage to the cylinder.

While four variations of the present poppet valve mechanism have been disclosed in detail herein, various other changes and modifications may be made to suit requirements, and the present valve mechanism may be used in various combinations of spool valve assemblies for both single and double acting cylinders, without departing from the scope of the invention.

I claim:

1. A valve for controlling the operation of a double acting hydraulic cylinder, comprising a body having a bore and a fluid inlet and two fluid outlet passages intersecting said bore, a spool in said bore extending through said outlet passages and having annular shoulders within said outlet passages, a poppet valve in each of said outlet passages, each including a cylindrical chamber with an annular valve seat defining a port and facing away from said spool, a cup-shaped element in said chamber having a conical surface engaging said seat and closing said port and having an orifice in the end adjacent to said port, a valve means for closing said orifice, a stem connected to said valve means and adapted to be engaged by the shoulder on said spool for opening said valve means, a cup-shaped member rigidly mounted in said chamber for reciprocably receiving and supporting said element and having a restricted orifice in the side thereof closed by said element when the element is fully retracted from its seat and another orifice in the end thereof communicating with said chamber, a valve means for closing said last mentioned orifice, and a coil spring within said element reacting between both said valve means for urging said valve means and said element to their respective seats.

2. In a valve for controlling the operation of a double acting hydraulic cylinder, a body having a bore and a fluid inlet and two fluid outlet passages intersecting said bore, a spool in said bore extending through said outlet passages and having shoulders within said outlet passages: a poppet valve in each of said outlet passages, each comprising a chamber with an annular valve seat defining a port and facing away from said spool, a hollow cylindrical element in said chamber having a surface engaging said seat and closing said port and having an orifice in the end adjacent to said port, a valve means for closing said orifice, a stem connected to said valve means and adapted to be engaged by the shoulder on said spool for opening said valve means, a means for reciprocably receiving and supporting said element and having a restricted orifice in the side thereof closed by said element when the element is fully retracted from its seat and another orifice in the end thereof communicating with said chamber, a valve means for closing said last mentioned orifice, and a spring means re-

acting between both said valve means for urging said valve means and said element to their respective seats.

3. A valve for controlling the operation of a hydraulic cylinder, comprising a body having a bore and a fluid inlet and a fluid outlet passage intersecting said bore, a spool in said bore extending through said outlet passage and having an annular shoulder within said outlet passage, a poppet valve in said outlet passage including a cylindrical chamber with an annular valve seat defining a port and facing away from said spool, a hollow cylindrical element in said chamber having a surface engaging said seat and closing said port and having an orifice in the end adjacent to said port, a valve means for closing said orifice, a stem connected to said valve means and adapted to be engaged by the shoulder on said spool for opening said valve means, a cup-shaped member rigidly mounted in said chamber for reciprocably receiving and supporting said element and having a restricted orifice in the side thereof closed by said element when the element is fully retracted from its seat and another orifice in the end thereof communicating with said chamber, a valve means for closing said last mentioned orifice, and a coil spring within said element reacting between both said valve means for urging said valve means and said element to their respective seats.

4. In a valve for controlling the operation of a hydraulic cylinder, a body having a bore and a fluid inlet and a fluid outlet passage intersecting said bore, a spool in said bore extending through said outlet passage and having a laterally extending surface within said outlet passage: a poppet valve in said outlet passage, comprising a chamber with a valve seat defining a port and facing away from said spool, a hollow cylindrical element in said chamber having a surface engaging said seat and closing said port and having an orifice in the end adjacent to said port, a valve means for closing said orifice, a stem connected to said valve means and adapted to be engaged by said surface on the spool for opening said valve means, a means for reciprocably receiving and supporting said element and having a restricted orifice in the side thereof closed by said element when the element is fully retracted from its seat and another orifice in the end thereof communicating with said chamber, a valve means for closing said last mentioned orifice, and a spring means reacting between both said valve means for urging said valve means and said element to their respective seats.

5. In a valve for controlling the operation of a hydraulic cylinder, a body having a bore and a fluid inlet and a fluid outlet passage intersecting said bore, a fluid control means in said bore extending into said outlet passage and having a laterally extending surface within said outlet passage: a poppet valve in said outlet passage, comprising a chamber with a valve seat defining a port and facing away from said control means, a hollow cylindrical element in said chamber having a surface engaging said seat and closing said port and having an orifice in the end adjacent to said port, a valve means for closing said orifice, a means adapted to be engaged by said surface on the control means for opening said valve means, a means for reciprocably receiving and supporting said element and having a restricted orifice in the side thereof closed by said element when the element is fully retracted from its seat, and a spring means for urging said valve means and said element to their respective seats.

6. A valve for controlling the operation of a hydraulic cylinder, comprising a body having a bore and a fluid inlet and a fluid outlet passage intersecting said bore, a fluid control means in said bore intersecting said outlet passage and having a laterally extending surface, a poppet valve in said outlet passage, comprising a chamber with a valve seat defining a port and facing away from said control means, a hollow cylindrical element in said chamber having a surface engaging said seat and

closing said port and having an orifice in the end adjacent to said port, a valve means for closing said orifice, a means adapted to be engaged by said surface on the control means for opening said valve means, a means for reciprocably receiving and supporting said element and having a restricted orifice in the side thereof closed by said element when the element is fully retracted from its seat and another orifice in the end thereof communicating with said chamber, a valve means for closing said last mentioned orifice, and a spring means for urging said valve means and said element to their respective seats.

7. In a control valve, a poppet valve, comprising a means defining a chamber and a valve seat therein, a hollow cylindrical element in said chamber having a 15 conical surface engaging said seat and having an orifice in the end adjacent said seat, a valve means for clos-

ing said orifice, a means for opening said valve means, a cup-shaped member for reciprocably receiving and supporting said element and having a restricted orifice in the side thereof closed by said element when the element is fully retracted from its seat and another orifice in the end thereof communicating with said chamber, a valve means for closing said last mentioned orifice, and a spring means for urging said valve means and said element to their respective seats.
